UNITED STATES PATENT OFFICE.

UMBERTO VALENTINI, OF ROME, ITALY, ASSIGNOR TO LAMBERTO LOMBARDI.

BUILDING HEATING DEVICE.

Application filed April 21, 1923. Serial No. 683,815.

To all whom it may concern:

Be it known that I, UMBERTO VALENTINI, subject of the King of Italy, residing at Rome, Italy, have invented certain new and 5 useful Improvements in a Building Heating Device, of which the following is a specification.

The object of the present invention is a heating device or arrangement in which the 10 heat necessary to elevate the temperature of the water circulating into the conduits and radiators is produced by an electric arc deflected by magnetic field in order to direct it against the heating surface of the boiler. 15 The heating arrangement forming the object of this invention is self adjusting, so that, beside the advantage of the immediate and instantaneous heating effect of the arc, there is also the other advantage of a great 20 economy, as the consumption of electric power controlled according to requirements.

The arrangement above referred to is illustrated in the accompanying drawing which is given in a diagrammatical way 25 only to show the principal points of the invention.

In the said drawing:

Fig. 1 is a side and perspective view of the arrangement showing the boiler, its support 30 and the water pipes in the immediate vicinity of the boiler;

Figs. 2 and 2^a are two sections of the said boiler, one being a transversal and another a longitudinal section of it;

Fig. 3 is a diagrammatical illustration of the arrangement of the regulating magnet and of the levers connected thereto which cause the movements of the electrodes supporting carriages; and

Fig. 4 is a diagrammatical view of the arrangement of said electrodes supporting cars and of the magnet that produces the arc deflecting magnetic field.

The boiler 5 of any suitable shape and 45 material, but preferably made as it is shown by the sectional views of Figs. 2 and 4, is made of a double wall of metallic sheet, and with a heating chamber 24 at its lower side. The boiler stands on a convenient 50 frame support 1 partly surrounded by sheet walls and having two compartments 3 and 4, with upper support 2 made of noncombustible metal having in its center a hole 23 (Fig. 4) for the passage of the flame of the arc. 55 On the bottom 4^a of the lower chamber 4 rests the electrodes adjusting device (Fig.

3) that consists of a magnet 19 having a longitudinally movable armature 20 connected with the ends of the crank levers 21, the other ends of which pass through the 60 partition 3^a that divides the chamber 4 from the chamber 3 and are provided with forked ends 22^a engaging depending pins 22 carried by the wheel mounted electrode carriages 17. A spring 23 coacting with an 65 arm 25^a on one of the levers 21 normally tends to separate the carriages 17.

A magnet 16 is placed between the said carriages 17 in such a position that its magnet field acts on the electric arc formed between 70 the points of the electrodes 18 and deflects it more or less according to the degree of energization of said magnet.

The arrangement is completed by the following members: a T joint 6 connecting the 75 boiler 5 with the hot water pipe 7 conducting hot water to radiators or the like, and also connected with the self acting regulating device 9.

A cold water return pipe 8 is also connected with the boiler 5.

A rigid iron bracket 11 is fixed on the lower end of the T joint 6, whilst its upper ends passes through a hole made on the 85 upper arm of the bracket 11 in which the pipe 12 may freely slide. To the said pipe 12 is connected an articulated system of 90 levers 13 in contact with the circuit breaker 14 that opens or shuts the circuit as it may easily be understood on examination of the drawing (Fig. 1).

The arrangement operates as follows:

When the circuit is closed at 14, the current flows in to the coil 16 and to the electrodes 18; but as these are not in contact 95 with one another there will be no arc formed between them. A portion of the current that passes into the coil 19 and attracts the armature 20 will cause the latter to pull down the levers 21 and by means of the pins 22 the carriages 17 will be moved towards one another until an arc is formed between the points of the electrodes 18. At the same time the magnet 16 will be excited and its field will cause said arc to be deflected into the space 24 and hit the heating surface of the boiler 5 with great energy so that the water contained in said boiler will be heated in a short time. The circulation of hot 100 water into the piping will then take place 105 in the known manner for this kind of heating system.

A convenient resistance inserted into the arc will cause a greater or less quantity of current to arrive to coil 19, which being more or less excited, will attract or repel the core 5 20 and by means of the crank levers 21 and rods 22 it will cause the cars 17 to move to and fro, and respectively increase or decrease the power of the arc, so that the temperature sent beneath the boiler will be 10 greater or less according to need.

Having so described the present invention, its nature and how it operates to perform the desired effect of heating the water of the conduit, I now declare that what I claim 15 is:

1. In a heating apparatus, a boiler including a bottom provided with a heating chamber, an electric arc producing device arranged in said chamber to heat said boiler,

and electromagnetic means so arranged with 20 respect to the electric arc producing device as to deflect the arc in the direction of the boiler.

2. In an apparatus as claimed in claim 1, the provision of means for automatically 25 regulating the electromagnetic means.

3. In a heating apparatus, electrodes, relatively movable carriages supporting said electrodes, levers connected with said carriages, electromagnetic means for actuating 30 said levers and carriages.

4. An apparatus as claimed in claim 1 characterized by the provision of an electric circuit including the arc producing devices and electromagnetic means, and thermo-sensitive means interposed in said circuit for controlling said devices and said means.

UMBERTO VALENTINI.
